UNITED STATES PATENT OFFICE.

WILLIAM LOUDEN, OF FAIRFIELD, IOWA.

HAY-CARRIER APPARATUS.

SPECIFICATION forming part of Letters Patent No. 559,588, dated May 5, 1896.

Application filed June 14, 1892. Serial No. 436,683. (No model.)

To all whom it may concern:

Be it known that I, WILLIAM LOUDEN, of Fairfield, in the county of Jefferson and State of Iowa, have invented certain new and useful

5 Improvements in Hay-Carrier Apparatus; and I do hereby declare the following to be a full, clear, and exact description of the invention, such as will enable others skilled in the art to which it appertains to make and 10 use the same.

My invention relates to an improvement in hay-carriers, the object of the invention being to produce a carrier constructed and arranged in such manner that an elevating-pulley 15 may be automatically locked to the carrier and permitted to have a free swinging movement without coming into conflict with the carrier-pulleys or wedging in the frame of the carrier.

20 A further object is to produce an improved locking device which shall be automatic in operation, simple and compact in construction, and effectual in the performance of its functions.

25 With these objects in view the invention consists in certain novel features of construction and combination and arrangements of parts, as hereinafter set forth, and pointed out in the claims.

30 In the accompanying drawings, Figure 1 is a side elevation showing my improvements. Fig. 2 is a sectional view on the line xx of Fig. 1. Fig. 3 is a cross-section on the line yy of Fig. 1 and showing a suspending-bracket bolted to the track-rail. Fig. 4 is a 35 separate view of the bracket. Fig. 5 is a separate view of the elevating-pulley. Fig. 6 is a view, also on line yy of Fig. 1, showing the carrier in engagement with the stop on the 40 rail and the grappling-hooks in position to release the elevating-pulley. Fig. 7 is a vertical section of the grappling devices.

A represents a wooden rail upon the sides of which metallic trackways b are secured.

45 These trackways are preferably of rolled-steel angles, having holes at intervals in their vertical flanges, through which they are secured by bolts to the rail, while the horizontal flanges project above the vertical flanges

50 and form trackways for the carrier-wheels to run on, as shown in drawings. It is prefer-

able that the trackways be secured to the rail a little below its longitudinal center, so that the carrier-wheels will not extend much, if any, above it.

55

The track is supported from the rafters or other timbers of the building in which it is used by means of brackets B , which are secured to said timbers and also at intervals to the rail A . These brackets, one of which is 60 shown in Fig. 3, are provided with two curved wings a , projecting horizontally from the center, and have perforations a' , through which they are fastened by nails or bolts to the rafters. To strengthen the bracket, which is 65 made thin and light, a flange a^4 is extended laterally from one side of its lower edge, and this flange is enlarged at the center. In said enlargement an elongated hole a^2 is made for the passage of the bolt a^3 , which secures the 70 bracket to the rail. By this means a light and yet strong track-suspending bracket is produced, and the bolt a^3 will be free to swing sidewise to some extent in the elongated hole a^2 and let the track swing sidewise, as 75 may be required in operation. The rail A being secured directly to the bracket by means of the bolt a^3 , the track is very simply and cheaply suspended and is held closely up to the supporting-timbers.

80

The carrier C has side plates constituting its frame, between which the rope-wheels C' are mounted, and above these wheels the plates are joined together so as to form rope-guards I . Each of these side plates is provided with two upwardly-projecting arms c' , which carry wheels c , adapted to run on the trackways b . These plates are also provided at their centers with inwardly-projecting lugs d , between which locking-dogs D are pivoted 90 so as to stand crosswise of the carrier-frame.

The bodies of the dogs D are horizontally disposed, and their ends extend out through openings in the sides of the carrier. The dogs are also provided with vertically-extending 95 ends having beveled faces d' , which in passing are adapted to be struck by the depending prongs e^5 of the stop-plate e^6 , which is secured to the under edge of the rail A , so as to raise the outer ends of said dogs.

Grappling devices E are pivoted near their centers in the frame of the carrier by means

100

of bolts or rods e' , which pass longitudinally through outwardly-projecting lugs e^2 on the carrier sides, so as to dispose the devices in substantially a vertical position and to give their upper and lower ends alternate movement to and from the longitudinal centers of the track and carrier. Their upper ends e^3 are forked and adapted to catch the depending prongs e^5 of the stop-plate e^6 between them, and thus hold the carrier stationary on the track. Their lower ends are provided with hooks F , which in turn are adapted to catch and hold the frame of the elevating-pulley G' .

15 Near the central parts of the grappling devices are formed inwardly-projecting tongues f , which are adapted to be turned upwardly by the ascent of the elevating-pulley and thus release the forks e^3 from the prongs e^5 and at the same time bring the hooks F into engagement with the frame of the elevating-pulley. The grappling devices will be held in this position by the outer ends of the dogs D dropping behind lips e on the devices above 20 the points where they are pivoted. The carrier now being released from the stop on the track and the hooks F being locked to the frame of the elevating-pulley it will be free to traverse the track and will carry the load 25 along with it. The carrier being returned to the stop, the ends of the forks e^3 on the sides of the grappling devices approaching it will pass by the prongs e^5 . The prongs e^5 will now strike the beveled faces d' of the dogs D and 30 will lift their outer ends from behind the lips e of the grappling devices E , which will permit their forked ends e^3 to move inwardly and catch the prongs e^5 between them and hold the carrier stationary on the track, while their 35 hooks F will move outward and release the pulley-frame. To assist in this movement, springs G^2 may be applied so that one end will bear against the carrier-frame and the other against the grappling device. The outer 40 faces e^4 of the forks e^3 may also be made divergent or beveled, so as to slip more readily around the stop-prongs e^5 and permit the forks to catch against them.

The tongues f of the grappling devices E 45 are made with forked ends f^2 , so as to lap on each other and communicate the movement of the one to the other. One of the forks f^2 on each of the tongues f is upwardly inclined, while the other one is downwardly inclined. 50 The upwardly-inclined fork on each tongue will catch over the downwardly-inclined fork on the opposite tongue, while the downwardly-inclined fork will catch under the opposite upwardly-inclined fork, and the grappling devices by this arrangement will always move 55 in unison.

The side plates of the carrier-frame are provided with recesses h , into which the hooks F pass when released from the pulley-frame, thus protecting the hooks and forming resting-places for them. The dogs D are also fitted with extended heels f' , so that in case

they should fail of their own gravity to drop behind the lips e the tongues f will strike the heels f' and force the dogs into position.

The frame of the carrier is made so as to form a throat H in its center, substantially in the shape of the main part of the pulley-frame G in horizontal section and large enough to admit the upper part of the pulley-frame. At the ends of the throat on each side are shoulders i , which extend inwardly at substantially right angles from the sides of the throat to a point even with or a little beyond the sides of the rope-wheels C' . These shoulders form abutments against which the edges of the pulley-frame G may rest when it enters the throat H . The upper part of the pulley-frame is made circular in form, and on each side is provided with lips l , which are concentric with the periphery of the pulley G' . When these lips l are in engagement with the hooks F , as already described, the pulley-frame will be free to swing longitudinally on the hooks to a considerable extent, and it will be held by the shoulders i from striking the rope-wheels C' or wedging fast in the frame of the carrier.

The entire apparatus is very simple and compact in construction, easy to manipulate, and effectual in the performance of its functions. The locking-dogs being pivoted to operate at right angles to the track and being mainly disposed horizontally take up very little room below the track, and therefore the elevating-pulley can be drawn up with its load closer to the track than can be done with carriers of common construction.

The space occupied by the vertical parts of the locking-dogs is mostly compensated for by the opening between the prongs e^5 , between which the vertical ends are adapted to pass. The rope-guards I can also be set closer up to the track and the rope-wheels C' set higher up, on account of the open space through the center of the track-stop.

The carrier is designed to operate in either direction along the track from the stop e^6 , and when power is applied to one end of the rope the other end is made fast to the carrier by tying a knot in it, or by other means well known to those skilled in the art. The object of making the upper ends of the grappling devices forked is not only to enable them to operate in either direction from the stop, but also to prevent the carrier from running back past the stop when operating on one side of it only.

What I claim as new, and desire to secure by Letters Patent, is—

1. A suspending-bracket for hay-carrier track of thin perforated metal, having extended wings, a lateral flange on the lower edge of said wings and an enlargement in the center of said flange, said enlargement having an elongated hole therein, substantially as and for the purpose set forth.

2. A track-stop having a depending prong on each edge in combination with grappling-

hooks adapted to engage an elevating-pulley, and locking-dogs, having vertical ends and pivoted to swing at right angles to the carrier-track and engage the grappling-hooks, 5 said vertical ends being adapted to be struck by the depending prongs of the stop to release the grappling-hooks, substantially as set forth.

3. A stop secured to the lower edge of the 10 track and having prongs on its edges, in combination with a carrier having suitable lock mechanism to engage the stop and a rope-guard on its frame adapted to pass between said prongs, substantially for the purpose set 15 forth.

4. Grappling-hooks pivoted in the sides of the carrier-frame, in a substantially vertical position, so as to engage the frame of the elevating-pulley, in combination with dogs to 20 lock said hooks in engagement with said pulley-frame, and a stop to release the dogs, said dogs being pivoted to move at right angles to the track, and their bodies being disposed in a substantially horizontal position.

5. A pair of grappling devices pivoted in the sides of the carrier-frame so as to stand in a substantially vertical position and have movement at right angles to the carrier-track, the lower ends of said grappling devices being adapted to engage and support a pulley-block, and their upper ends to engage a stop and hold the carrier stationary on the track, and dogs to hold said grappling devices so that their upper ends will be released from 35 the stop and their lower ends locked to the pulley-block, substantially as set forth.

6. Grappling devices pivoted in the sides of the carrier-frame in a substantially vertical position, so as to have movement at right 40 angles to the track, their upper ends being forked to catch a stop on the track, their lower ends hooked to engage the frame of the elevating-pulley, and dogs to hold said grappling devices released from the stop and 45 locked in engagement with the pulley-frame.

7. The combination with a carrier-frame having a throat therein, of grappling devices pivoted at each side of the throat, said grappling devices having hooks at their lower ends 50 adapted to engage the frame of the elevating-pulley, upwardly-extending arms adapted to catch on a stop on the track and tongues ex-

tending inwardly across the throat of the carrier, adapted to be struck by the elevating-pulley so as to release the arms from the stop 55 and to bring the hooks into engagement with the frame of the pulley, and dogs to lock the grappling devices in this position, substantially as set forth.

8. The combination with a track and stops 60 projecting therefrom, of a carrier, grappling devices pivoted thereto, said grappling devices each having a pair of upwardly-projecting arms, and dogs lying between these upwardly-projecting arms in position to be 65 struck by the stops and release the grappling devices, the arms on the grappling devices being adapted to straddle the stops when released by the dogs, substantially as set forth.

9. The combination with a track and a stop 70 thereon, of a carrier, grappling devices pivoted thereto and adapted to engage said stop, said grappling devices having inwardly-projecting tongues, a pulley-frame adapted to strike said tongues, dogs pivoted between 75 said grappling devices to effect their locking to the pulley-frame, said dogs being provided with elongated heels adapted to be struck by the tongues, substantially as and for the purpose set forth.

10. The combination of a carrier having a throat therein, grappling devices pivoted in the sides of the carrier, and having forked tongues extended inwardly across the throat of the carrier so as to catch on each other and 85 communicate movement, one to the other, and a pulley-frame adapted to strike said tongues, substantially as and for the purpose set forth.

11. The combination of a hay-carrier having a throat therein, a pulley-frame adapted 90 to enter the throat and be locked to the carrier, said throat being provided with shoulders forming abutments for the pulley-frame, and the pulley-frame being adapted to rest against said abutments and swing in said 95 throat, substantially as set forth.

In testimony whereof I have signed this specification in the presence of two subscribing witnesses.

WILLIAM LOUDEN.
